Application April 30, 1930, Serial No. 448,613

16 Claims. (Cl. 175—354)

This invention relates to a container of condensable gas in which electrodes are provided to pass intermittent unidirectional electron discharges to an anode located in a low pressure part of the container. It pertains particularly to a container of mercury vapor having an electron-emitting cathode, such as a pool of mercury or an incandescent filament in vapor, in addition to the anode, and to a system in which it is used.

One object is to provide the container with an anode chamber in which the required high rarefaction is simply, efficaciously and efficiently maintained. Another object is to initiate an electron discharge thru the highly rarefied part of the discharge path, and also to control the electron flow when it is desired to produce high frequency discharges. A further object is to provide a system, comprising suitable sources of current and potential, to utilize the highly rarefied anode space.

These objects are attained by providing the container with a novel condensing chamber adjacent to the discharge path near the anode chamber, by varying the gas pressure in the anode chamber, by reducing the arc-initiating voltage with suitably disposed conductors, by introducing a periodically variable electrostatic field into the discharge path, and by providing other features of the system which will be pointed out in the following detailed description of the invention.

The term, condensing chamber, is used herein to refer to a space in a tube provided primarily for condensing vapor, hence it contains neither an electrode nor a discharge path which heat the chamber and thereby tend to prevent condensation. The word, cathode, refers to a conductor capable of emitting electrons and anode refers to a conductor in the tube capable of collecting and absorbing electrons.

I vary the breakdown value of the discharge path by placing a charged surface adjacent to the path so as to suitably influence its space charge independently of, or in addition to, that produced by its terminal electrodes. Decreasing the negativity of the space charge decreases the potential required to break down the path and increasing it has the reverse effect. Any means for collecting electrons or positive ions from the path will influence its breakdown value for any given electrical state of the electrodes at the terminals of the path.

The drawings, forming part of this specification, illustrate the novel features of the invention. Figure 1 shows a tube in a system for

initiating, sustaining and controlling electron discharge. Figure 2 shows a modified form of the anode chamber. Figure 3 shows an auxiliary condensing chamber located adjacent to the discharge path of a rectifier tube.

In Figure 1 the Pyrex glass tube 2 consists principally of a mercury cathode 3, a main condensing chamber 4, an anode arm 5 terminating in a nozzle 6, an auxiliary condensing chamber 7 having a mercury trap 8 at its lower end, a condensed mercury return tube 9, an anode chamber 10, and a float chamber 11. Adjacent to the cathode 3 is an arc-starting arrangement which includes mercury 12, glass float 13 in chamber 11, an iron solenoid-core 14 in the upper part of 15 13, a leading-in conductor 15, and a solenoid winding 16. The anode chamber 10 contains an electron-supply anode 20, a control conductor 21, and a diverted-electron-flow anode 22. The control conductor 21 is water-cooled by water passing thru tubing to, and from, a jacket 25 surrounding the metallic tube 21. The metal-to-glass seals 23 and 24 are also water cooled. The source of water flow is insulated from anode 22 and from anode 20 which is grounded.

The anode arm 5 is provided with conducting bands 30 and 31. The band 30 consists of a high resistance metallic film on the glass of nozzle 6 and is connected conductively to the band 31 by the leading-in wire 32.

The circuit for producing a starting arc between mercury 12 and mercury cathode 3 includes a switch 35, a battery 36 and a current limiting resistance 37.

The circuit for starting and sustaining the ionizing arc between anode 20 and cathode 3 comprises a direct current generator 40, an iron-core inductance 41, an air-core inductance 42, and a resistance 43 in series between anode 20 and cathode 3. A multi-contact oil switch 44 is placed in parallel with the discharge path between 20 and 3 and part of resistance 43. The anode 20 is connected to bands 30 and 31 thru condenser 45. The current supply conductor 46 to anode 20 is insulated by quartz tube 47 inside the anode chamber.

The diverted-flow-anode supply circuit comprises a direct current generator 50, an iron-core inductance 51, an air-core inductance 52, and a resistance 53 connected in series between anodes 20 and 22. Condenser 54 in series with inductance 55 are placed in parallel with the discharge path between anodes 20 and 22. An energy absorbing circuit 56 is coupled to inductance 55.

The control circuit includes the secondary winding of a high frequency current transformer 60, a high resistance 61 in parallel with condenser 66, a switch 62, and a battery 63 connected in series between anode 20 and control conductor 21. The primary of transformer 60 is connected to a source 64 of high frequency current which has a lower frequency than the natural frequency of a simple circuit consisting of condenser 10 54 and inductance 55 in series.

The auxiliary condensing chamber 7 is placed in a liquid bath comprising the container 70, liquid 71, coils 72 and 73 of tubing immersed in the liquid, a source 74 of heat from which hot fluid 15 can be passed thru coil 72, and a source 75 of cold from which a cold fluid can be passed thru coil 73. Water or a refrigerant gas provides a suitable cold fluid.

A heat-insulating cap 80 is provided to fit over 20 the main condensing chamber. The vapor pressure in arm 5 may be varied by raising or lowering this cap.

The operation of the tube and associated 25 equipment consists in starting an arc between mercury 12 and cathode 3, initiating and sustaining electron discharge from cathode 3 to anode 20, and producing intermittent electron discharges in the anode chamber between anodes 20 and 22. A more detailed description of the 30 function and operation of each part of the tube and of each exterior unit of the system follows.

A starting arc is formed between mercury 12 and cathode mercury 3 by energizing winding 16 to pull down the float 13 which displaces mercury 12 thereby making contact between 12 and 35 3 so that current flows from the battery 36 thru resistance 37 and switch 35; then 16 is de-energized, the float 13 rises, and mercury 12 breaks contact with mercury 3 thereby forming a cathode spot on mercury 3.

An arc is next initiated between electron supply 40 anode 20 and cathode 3 by first heating coil 72 to increase the vapor pressure in the auxiliary condensing chamber 7; then the direct current generator is loaded by closing switch 44 to pass a relatively large current thru iron-core inductance 41; and, finally the current is broken so that a high rate of change of current in 41 produces a sufficiently high positive potential on 45 anode 20 with respect to cathode 3 to initiate a discharge. The potential required to initiate a discharge is reduced by the relatively high vapor pressure in chamber 7 and by the decreased negativity of the space charge produced by the bands 50 30 and 31. After a sustained discharge of constant value has been established between 20 and 3, the switch 35 is opened, heat supply to coil 72 is stopped, and cooling fluid is supplied to coil 73 to cool chamber 7 to the desired temperature.

A relatively small amount of vapor is condensed 55 in chamber 7 compared with the amount condensed in chamber 4; this greatly reduces the amount of cooling medium required to keep 7 at the proper temperature. The amount of cooling medium required is further reduced by the mercury condensed in 7 being returned to the cathode thru tube 9 instead of thru arm 5 where re-evaporation would take place. The diffusion pump action of the vapor flowing from nozzle 60 to chamber 7 reduces the pressure of non-condensable gas which may exist in the anode chamber. In the discharge path a high vapor pressure exists between the nozzle and the cathode compared with the pressure between the nozzle 70 and the anode; tubes having this feature have

been used in the past but the pressure used in both the high and low pressure parts of the path was much greater and no special means, such as conductor 30, heat source 74, or switch 44, were required to initiate electron flow to anode 20. One of these novel features may be provided to operate the tube described by Szilard in Patent 1,697,210 in order to reduce the required operating voltage or to make the tube operate at lower gas pressures surrounding the grid and 10 anode. The auxiliary condensing chamber 7 which is adjacent to the discharge path is heated comparatively little by heat radiated by the discharge. The lowest temperature of any part of chamber 7 largely determines the vapor pressure 15 in the anode chamber 10 so that the pressure surrounding the anodes 20 and 22 can be varied by varying the temperature of chamber 7. As the temperature of 7 decreases below a certain value, the arc-drop thru the low pressure part of the discharge path increases due to 20 decreased vapor pressure until electron-supply anode 20 becomes incandescent and constitutes a source of secondary electron emission; as the arc-drop increases the tendency for the arc to 25 become extinguished increases; this tendency can be overcome, to a certain extent, by increasing the potential of source 40 and also by reducing the capacitance between anode 20 and the cathode to a minimum. 30

The anode 20 may be placed in anode arm 5 or in the main chamber 4 to reduce the voltage drop between 20 and the cathode but the potential required on anode 22 to divert electron flow will thereby be increased. 35

The diverted-flow anode supply circuit supplies the energy for the high frequency current output of the system. From generator 50 a direct current flows thru choke coils 51 and 52 to either the anode 22 or to condenser 54 to 40 produce linear-sinoidal oscillations in the discharge circuit comprising 54 and 55. The energy of the oscillations is absorbed by an antenna, an absorbing circuit 56, or other energy consuming arrangement. These oscillations are produced by 45 making the gas-space between anodes 20 and 22 alternately conducting and non-conducting at a high frequency. When the space is conducting, electrons flowing from the cathode to anode 20 are diverted to anode 22; any secondary electrons emitted by 20 may also flow to 22. When the space is non-conducting, all electrons flowing from the cathode are collected by anode 20 and no electrons flow to anode 22. When the control conductor 21 is connected by switch 62 to anode 20, the conductor becomes charged sufficiently 55 negative with respect to anode 22 to prevent initiation of electron flow to anode 22 due to the increase of negativity of the space discharge produced by the negative bias. By superposing an alternating potential on the negative bias the potential of control conductor 21 becomes sufficiently positive during a high frequency cycle to instantaneously overcome, or neutralize, the negative effect to permit initiation of electron flow 60 to 22. It is thus seen that the frequency of electron discharges to diverted-flow anode 22 is determined by the frequency of the constant amplitude current source 64. The leakage resistance 61 allows the positive ion current, that is, 70 the current due to the positive ions collected by 21, to leak to anode 20 which is grounded. The proper value of the resistance depends on the degree of rarefaction inside of 21, on the potential impressed on conductor 21 by transformer 60, on 75

the value of the bias voltage of 20, and on the sense and value of the additional bias of battery 63.

The control conductor 21 has the novel feature 5 of having a single opening as distinguished from a grid having numerous mesh or openings thru which the electrons may flow; this construction assures that electron flow takes place always thru the same opening instead of 10 fortuitously thru alternative openings. Another characteristic feature is the comparatively large ratio of length to effective diameter of the discharge path thru the conductor; by constricting the path its length can be reduced and 15 the tendency to intermittent flow is increased. The collection of positive ions by conductor 21 during a greater part of a cycle causes it to become heated which may result in undesirable 20 secondary emission; this is prevented by water-cooling the conductor and by keeping the vapor pressure low by means of the auxiliary condensing chamber 7. Cooling the conductor 21 tends to make it immune to undesirable effects of positive 25 ion bombardment while reducing the gas pressure adjacent the conductor by chamber 7 reduces the number of positive ions present. The electrostatic field, inside of conductor 21 upon which the breakdown value of the space depends, increases in effectiveness as the gas pressure decreases. 30 The total electron flow from the cathode remains constant while the electron flow to anode 20 is periodically diverted to anode 22 by periodic variations of the electrostatic field. The magnetic field in conductor 21 is maintained constant by passing the sum of the currents to anodes 20 and 22 thru 21. The variations of magnetic field produced by variations of electron flow to anode 22 are neutralized by variations of magnetic field produced by variable current flowing 35 thru conductor 46.

To produce high frequency intermittent flow of electrons to anode 22 in the presence of a constant flow of electrons from the cathode to anode 20: Close switch 62, start generator 50 and then 40 start generator 60. The voltage required of generator 50 depends on the rarefaction, effective diameter, and length of the discharge path thru 21; it increases with decrease of diameter and with increase of length and rarefaction.

50 It is thus seen that electron-supply anode 20 functions as a virtual main cathode but does not become disintegrated in which respect it differs from an electron-emitting electrode. Among the 55 advantages of a virtual over an actual cathode are avoidance of disintegration or consumption of electrode material due to cathode sputtering and the consequent ability to maintain a relatively low and uniform gas pressure adjacent to the electrode. Other advantages such as control of 60 initial velocity of electrons, constant rate and rapid de-ionization, etc., are obvious to those skilled in the art.

Figure 2 shows a modified arrangement of the anode chamber 10 with respect to the electrodes 65 and especially the control electrode. The chamber 10 contains an electron supply anode 20, a positive ion collecting grid 26, control grids 221, and diverted-flow anode 22. A number of grids are connected internally or externally (as shown) 70 in parallel thru resistances 27. A battery 28 is provided to charge grid 26 negative with respect to anode 20 and the ground.

The electrical connection to control conductor 221 is similar to the connection to control conductor 21 of Fig. 1. Two types of electron-flow

control can be produced by conductor 221. I will refer to these types as voltage control and current control. The type described with reference to Fig. 1 is voltage control since the control conductor determines the voltage on anode 22 with respect to anode 20 at which electron flow to 22 begins. Current control is the type which takes place in three-electrode thermionic tubes; the control conductor determines the current flow to anode 22 which depends on the voltage-drop thru the tube while current is flowing. Current control in gas tubes is generally limited to relatively low voltages. The properties of such tubes have been described by Lübecke in the Zeitschrift für 15 technische Physik, Nr. 11 of 1927 and also in the Zeitschrift für Hochfrequenztechnik of July, 1928.

Assume that electron-flow to electron-supply anode 20 is taking place and that a somewhat smaller electron-flow passes to anode 22; under this condition a high frequency voltage of proper 20 value impressed on current control conductor 221 will vary the electron-flow to anode 22 periodically at the same frequency and thereby transmit energy to circuit 56. The grid 26 may be added to collect positive ions before they reach the lower 25 grid of 221. The anode 20 is made of two parallel perforated plates having staggered perforations to reduce the velocity of electrons at 20 which pass to anode 22. The control grid 221 is made of screen having a suitable size of wire and mesh 30 so that the electron discharge does not concentrate and flow thru a single opening or mesh.

To produce voltage control grid 26 is charged sufficiently negative to prevent any electron-flow to anode 20 being diverted to anode 22. A sufficiently high positive potential on grids 221 will neutralize the increased negativity of space discharge produced by grid 26 so that by making 221 periodically positive electron discharge will be diverted to anode 22 at the same frequency. 40

Figure 3 shows the upper part of an anode arm 305 of a multi-anode rectifier tube. The arm is provided with an auxiliary condensing chamber 307 which constitutes the novel feature of this construction. The temperature of the part of chamber 307 most remote from the discharge path determines, to a large extent, the vapor pressure surrounding anode 320 in the anode chamber 10 since the pressure can readily equalize; furthermore, the vapor density in the anode chamber is less than in the remote part of chamber 307 because the temperature is higher. The comparatively small amount of vapor which passes up the arm 305 produces diffusion pump action. The remote part of chamber 307 is heated slightly by 50 vapor from arm 305 and by heat radiated from the discharge. The small amount of mercury condensed in chamber 307 is returned to the cathode thru the return tube 309 which keeps the mercury cool by not letting it come in contact with the discharge path. 55

In a rectifier tube the mercury cathode emits electrons continually either by overlapping of phases or by a keep-alive current. It is known that in the presence of this continual emission 65 a very high positive potential must be impressed on the anode with respect to the cathode to initiate an electron discharge when a part of the discharge path is highly rarefied. This phenomenon is called "fading". The part of the path from 70 the anode to the nozzle 306 is highly rarefied so that means must generally be provided to reduce the voltage required to initiate electron flow at the beginning of each half cycle or transient flow period. For this purpose I provide a number of 75

piloting electrodes 34 which are charged thru condensers 331. This arrangement functions similarly to the band 31 of Fig. 1 to produce longitudinal piloting in the manner that I have described in my copending application, Serial Number 228,233; each piloting electrode 34 primes a discharge from the electrode 34 nearest above it.

The improvement illustrated by Fig. 3 has a number of advantages when compared with the usual arrangement of immersing the whole tube in oil. I have found that it is not desirable to cool the mercury of the cathode nor the cathode end of the discharge path in order to increase the voltage which can be rectified but that it is necessary, however, to reduce the vapor density near the anode. When a tube is immersed in oil all of the tube is cooled; the cathode which preferably should remain hot transmits heat to the oil which should remain cold. A continuous hot path is provided by the discharge from the cathode to the anode so that the vapor pressure surrounding the anode is determined by the temperature of the coolest part of the path and this temperature is relatively high due to the discharge. Compared with oil cooling a much smaller amount of cooling medium applied to chamber 307 will more effectively and efficiently produce the desired low density of vapor adjacent to the anode.

I have set forth the novel features of my invention in the following claims.

I claim:

1. A vacuum tube comprising a cathode having vapor adjacent thereto, at least two anodes, a vapor condensing surface between the cathode and one of said anodes arranged to be heated only by vapor condensing thereon, and a control surface capable of controlling electron flow to at least one of said anodes combined with a source of unidirectional current connected to divert 40 electron flow from one to the other of said anodes.

2. The combination of a mercury vapor tube comprising two anodes, means for maintaining the first of said anodes and the ground at the same potential, and means for maintaining the second of said anodes at an average positive potential with respect to the first of said anodes.

3. A vacuum tube comprising a discharge path having adjacent thereto a conducting surface in combination with means for varying, at high frequency, the electron-flow thru said path, and means for neutralizing the variation of magnetic field in said surface produced by said varying flow.

4. In a system for electron discharge a vacuum tube comprising an anode, a discharge path terminating at said anode, and a cooled control conductor capable of increasing the breakdown value of the space charge of said path, and electrical energy supply for charging said conductor with a potential varying at a radio frequency and 60 having an average negative value with respect to any positive ions adjacent thereto.

5. In a vacuum tube for electron discharge a condensing chamber, an anode, and a discharge path terminating at said anode, containing vapor, and divided into high and low pressure parts by said chamber combined with a composite surface comprising a plurality of elemental surfaces disposed in said high and low pressure parts, each capable of decreasing the breakdown value of 70 the space charge in said path.

6. In a system for electron discharge a vacuum tube comprising a cathode having vapor adjacent thereto, two anodes, a discharge path between said electrodes, and a condensing chamber, a 75 source of potential between the cathode and one

of said anodes, and a second source of potential arranged to maintain an average difference of potential between said anodes.

7. A mercury vapor tube having at least two anodes combined with a low impedance to high frequency current disposed between one of said anodes and the ground. 5

8. In a system for electron discharge a vacuum tube comprising two anodes combined with at least two conductors in parallel between said 10 anodes; one of said conductors comprising capacitance in series and the other of said conductors comprising the main source of unidirectional current energy supply to said tube.

9. In a system for electron discharge a vacuum tube comprising an anode and a discharge path terminating at said anode and containing vapor, means for starting and maintaining a continuous electron flow thru said path, and cooling means for decreasing the pressure of the vapor, after 20 said flow has been started, to the extent that the voltage drop thru the vapor adjacent the anode is thereby increased to a sustained fixed high value. 15

10. In a system for electron discharge a vacuum tube containing vapor at a pressure of less than 25 twenty microns of mercury and an anode surface adjacent thereto, a continuous electron flow to said surface, and means including a source of electrical energy for making said surface become 30 a virtual source of electrons. 30

11. A vacuum tube comprising a cathode having vapor adjacent thereto, an anode charged to a positive average potential with respect to the cathode, a second anode, a discharge path terminating at said second anode, and a cooled surface adjacent said path arranged to be charged with a varying potential to influence the potential required to break down said path combined with a source of potential arranged to charge said second anode to a positive average potential with 40 respect to the first-mentioned anode. 35

12. A vacuum tube comprising an electron-supply anode capable of supplying electrons by diversion, a diverted-flow anode, and a plurality of control surfaces separated by impedance and capable of influencing electron flow to said diverted-flow anode combined with a source of varying potential connected to said surfaces. 45

13. In a system for electron discharge a vacuum tube comprising two electrodes adjacent to gas capable of becoming a source of positive ions and a control surface therebetween arranged to avoid undesirable secondary electron emission therefrom caused by positive ion bombardment, an inductance and a capacitance in series connected 50 between said electrodes, and a source of potential containing two components connected to said surface; the first of said components being constant and the second being alternating at a frequency less than the natural frequency of said inductance and capacitance. 55

14. The method of operating a system for electron discharge which comprises passing a dual current thru rarefied gas by simultaneously producing electron flow to two surfaces and superposing an oscillatory current on the dual current during at least part of a cycle of the oscillatory current by producing a periodic flow of displacement current with continuous current energy. 65

15. The method of operating a vacuum tube provided with a discharge path terminating at an anode and containing vapor which comprises producing a vapor pressure in at least part of the path, in the presence of continuous electron 70 75

flow to the anode, of less than one half of its saturation value by diverting the flow of vapor from the path at a plurality of points along the path to surfaces having suitably low temperatures.

5. 16. A vacuum tube comprising a cathode having vapor adjacent thereto, an anode surface having a continuous flow of electrons impinging

thereon, cooling means including a vapor-condensing surface arranged to reduce vapor pressure adjacent said anode surface to the extent that the minimum potential drop between said electrodes is at least doubled, and a second anode surface charged to a positive average potential with respect to the first-named surface.

HENRY G. CORDES.
